UNITED STATES PATENT OFFICE.

FRANK N. COOKE, OF DANVERS, MASSACHUSETTS, ASSIGNOR TO ARABELLA C. COOKE,
OF DANVERS, MASSACHUSETTS.

AIR-FEEDING ATTACHMENT.

1,079,636.

Specification of Letters Patent. Patented Nov. 25, 1913.

Application filed January 29, 1913. Serial No. 744,968.

To all whom it may concern:

Be it known that I, FRANK N. COOKE, a citizen of the United States, residing at Danvers, in the county of Essex and State 5 of Massachusetts, have invented certain new and useful Improvements in Air-Feeding Attachments; and I do hereby declare the following to be a full, clear, and exact description of the invention, such as will enable others skilled in the art to which it 10 appertains to make and use the same.

This invention relates to apparatus for heating the air fed to the furnaces of power and heating plants; and it consists in the 15 novel construction and combination of the parts hereinafter fully described and claimed, whereby the air is heated to a relatively high temperature before being admitted to the furnace and so that its heated 20 oxygen is utilized to obtain a more perfect combustion of the combustible gases which are usually wasted to a great extent.

In the drawings, Figure 1 is a horizontal section of a portion of a furnace provided 25 with an attachment for heating the air according to this invention. Fig. 2 is a front view of the front baffle plate. Fig. 3 is a front view of the rear baffle plate. Fig. 4. 30 is a cross-section through the two baffle plates, taken on the line $\alpha-\alpha$ in Fig. 1.

A portion only of a furnace 2 is shown as the furnace is of any approved construction in which any kind of fuel can be 35 burned. This furnace has an opening 3 which may be the usual feed opening or door for fuel, or it may be a special opening formed at any convenient point. When this opening 3 is the feed opening for fuel it is usually provided with a hinged door 4 of 40 any approved make. The opening 3 is rectangular, and the door 4 extends over it and forms a supporting plate for the heating attachment.

The heating attachment comprises two 45 rectangular baffle plates 6 and 14. The baffle plate 6 is provided with projecting flanges 7 which form an unobstructed chamber 8 on its front face. A plate or washer 9 of asbestos or other non-heat-conducting material is arranged between the flanges 7 and the door 4, and the door 4 has an air opening 10 provided with a regulator or damper 11 in the usual way. A series of holes 12 is formed through the lower portion of the 50 baffle plate 6 for the passage of air. The 55

rear baffle plate 14 has projecting flanges 15 on its front face around its edges, and it has also partition plates 17, 18 and 19 which divide up its chamber into a tortuous passage or passages 20. The lower partition plates 17 are arranged around the air holes 12, and the partition plates 18 and 19 are arranged horizontally above them with connecting openings at their middle parts and ends alternately, so that the air is forced to 60 follow a very circuitous course. Air outlet holes 21 are arranged in a row through and at the upper part of the rear baffle plate 14, and the air passes from the upper convolution of the tortuous passage 20 into the 65 combustion chamber of the furnace. A mat or washer 24 of asbestos or other approved material is interposed between the partition plates and flanges of the rear baffle plate and the rear surface of the front baffle plate 70 in order to make a sufficiently air-tight joint. The baffle plates are secured together and to the door, or other part of the furnace which supports them, by any approved fastening devices, such as bolts 25. The two 75 baffle plates form a pair, and as many similar pairs of baffle plates as desired can be used when bolted together, or a single pair of baffle plates can be used. The oxygen of the air is heated to a very high temperature 80 as it passes through the chambers of the metallic baffle plates, and its efficiency in supporting combustion in the furnace chamber is thereby greatly increased.

What I claim is:

1. The combination, with a fire-box having a rectangular opening on one side, and a supporting plate extending over the said opening and provided with an air inlet at its upper part; of a front baffle plate secured to the rear side of the supporting plate and having flanges at its edges which form an unobstructed air chamber against the supporting plate and having a row of outlet holes in its back below the level of the air inlet; and a rear baffle plate secured to the rear side of the front baffle plate and having a row of outlet holes in the upper part of its back, and having flanges at its edges and partition plates projecting from its front face and forming with the back of the front baffle plate a tortuous air passage extending between the outlet holes of the front and rear baffle plates respectively.

2. The combination, with a fire-box hav-

ing a rectangular opening on one side, and a supporting plate extending over the said opening and provided with an air inlet at its upper part; of a front baffle plate secured 5 to the rear side of the supporting plate and having flanges at its edges which form an unobstructed air chamber against the supporting plate and having a row of outlet holes in its back below the level of the air 10 inlet; and a rear baffle plate secured to the rear side of the front baffle plate and having a row of outlet holes in the upper part of its back, and having flanges at its edges and partition plates projecting from its

front face and arranged horizontally in two 15 series and having openings at their middle parts and ends alternately and forming with the back of the front baffle plate a tortuous air passage extending between the outlet holes of the front and rear baffle plates 20 respectively.

In testimony whereof I have affixed my signature in the presence of two witnesses.

FRANK N. COOKE.
